CLAIM

We claim the ornamental design for a surgical instrument, as shown and described.

DESCRIPTION

FIG. 1 is a perspective view of a surgical instrument, showing our new design;

FIG. 2 is a top view thereof;

FIG. 3 is a bottom view thereof;

FIG. 4 is a front view thereof;

FIG. 5 is a left side view thereof, the right side view is a mirror image thereof; and,

FIG. 6 is a rear view thereof.

The broken lines in the drawings are for the purpose of illustrating portions of the surgical instrument that form no part of the claimed design.

1 Claim, 6 Drawing Sheets
